UNITED STATES PATENT OFFICE.

PAUL WINSOR, OF WESTON, MASSACHUSETTS.

CORNER-PIECE FOR WINDOW-SASHES.

1,069,309.

Specification of Letters Patent.

Patented Aug. 5, 1913.

Application filed May 8, 1911. Serial No. 625,675.

To all whom it may concern:

Be it known that I, PAUL WINSOR, a citizen of the United States, residing in Weston, county of Middlesex, and State of 5 Massachusetts, have invented an Improvement in Corner-Pieces for Window-Sashes, of which the following description, in connection with the accompanying drawings, is a specification, like letters on the drawings 10 representing like parts.

This invention relates to a corner piece for window sashes to facilitate cleaning of the glass in the corners, and has for its object to provide a simple, inexpensive and 15 efficient device, which is applied to the glass when set and is retained in its operative position as will be described.

The corner pieces may be made of substantially thin material, such as sheet metal, and 20 are shaped to lie flat against the glass pane, so that when the glass pane is set in the sash, the corner pieces are secured in permanent relation to the glass pane and its sash by the means employed to secure the glass pane to 25 the sash.

These and other features of this invention will be pointed out in the claims at the end of this specification.

Figure 1 is an elevation of a sufficient portion of one form of window provided with 30 corner pieces to enable the invention to be understood. Fig. 2, a detail in vertical section on an enlarged scale to be referred to. Fig. 3, a horizontal section on the line 3—3. 35 Fig. 2. Fig. 4, a detail of the form of corner piece shown in Figs. 1 to 3, inclusive. Figs. 5 and 6, details in section to illustrate a modified form of corner piece, and Fig. 7, a detail of the corner piece shown in Figs. 40 5 and 6.

Referring to the drawing, *a* represents a window sash of any suitable or desired construction and provided with one or more panes *b* of glass, which are secured to the 45 sash by putty *c* in the usual manner.

In accordance with this invention, each pane of glass is provided with a corner piece *d* for each corner, each of which corner pieces is designed to cover the corner of the 50 glass and thereby enable the exposed portion of the glass to be kept clean with the least possible labor. The corner piece *d* is designed to be applied to the glass pane when the latter is set, and in the present instance, 55 the corner piece is provided with a lip or

member adapted to engage the edge of the glass.

To facilitate application of the corner pieces and to reduce the cost of the same and also of applying them to the window, I may 60 prefer to make the corner piece after the manner shown in Fig. 4, so that the corner piece can be applied to either side of the glass pane. To this end the corner piece *d* shown in Fig. 4, is provided with a body 65 portion, which engages the face or side of the glass, said body portion having two edges 10, 12, at right angles to each other and with a curved front edge 13. One edge, as 10, is provided with a projection 14 extending from the outer end of the edge 10 toward but not to the inner end thereof, and the edge 12 is provided with a like projection 16, which extends from the inner end of the edge 12 toward the outer end thereof. 70

The projections 14, 16 are designed to be bent substantially at right angles to the corner piece in the same direction, so that when the corner piece is applied to one side of the glass pane, they will engage the meeting edges of the glass, and said projections are located as described, so that when a duplicate corner piece is applied to the opposite face of the glass pane, the projections on the duplicate will register with the unflanged portions of the edges, as clearly represented in Figs. 2 and 3. The corner pieces can thus be applied to the glass pane before the latter is set in its frame or sash, and are retained in fixed or permanent relation to the sash by the means employed to secure the glass to the sash, namely, the bead *c* of putty and the lip 21 on the sash. 75

I prefer to make the corner piece as represented in Fig. 4, but it is not desired to 80 limit the invention in this respect, as the corner pieces may be made in other forms, as for instance, in Fig. 7, two corner pieces are shown as made from a single piece of sheet metal or other thin material and 85 folded on the lines 23, 24, to form one projection 25 to engage one edge of the glass, the other projection 26 being formed on one half of the blank. 90

In operation with the device shown in 105 Fig. 7, the blank is folded on the lines 23, 24, at one edge of the glass and the projection 26 is folded over the other edge of the glass as represented in Figs. 5 and 6.

I prefer to provide the corner pieces with 110

the curved edge 13, but it is not desired to limit the invention in this respect, as said edge may be of other shapes.

From the above description, it will be seen that the corner pieces *d* serve to prevent dirt from accumulating in the corners of the sash and also enable the glass to be cleaned more thoroughly and in the most effective manner. Furthermore the window can be provided with corner pieces at a minimum expense.

Claims.

1. The combination with a window sash, a glass fitted thereto, and means for securing said glass to said sash, of substantially flat corner pieces interposed between said glass and its securing means to enable the said pieces to be applied to the glass before it is set and to be retained by said securing means, substantially as described.

2. The combination with a window sash, a glass fitted thereto, and means for securing said glass to said sash, of corner pieces

therefor fitted into the corners thereof to contact with the side of the glass, and having projections on their edges adjacent to the window sash, said corner pieces being retained in position by the said securing means, substantially as described.

3. A corner piece for windows comprising a substantially thin body portion capable of being applied to the side of the window glass and provided with meeting edges substantially at right angles to each other, one of said edges having a projection removed from the junction of said edges and the other edge having a projection adjacent to the junction of said edges, for the purpose specified.

In testimony whereof, I have signed my name to this specification in the presence of two subscribing witnesses.

PAUL WINSOR.
